MAINSPRING TENSION INDICATOR FOR
WATCHES AND SIMILAR MECHANISMS

Carl U. Frennesen, St. Paul, Minn.

Application July 5, 1945, Serial No. 603,328

5 Claims. (Cl. 185—44)

1

This invention relates to means operable by the main spring of a watch or similar mechanism for indicating on a dial or scale the state of tension of the spring and/or for stopping an automatic spring winding device when the spring is fully wound.

It is an object of my invention to provide simple, compact and efficient mechanism of this class whereby an observer is enabled to determine at a glance the state of tension of the main spring of a clock, watch or other mechanism having a rotary spring-actuated member and a rotary winding member disposed in parallel and coaxial relation to the spring-actuated member.

A further object is to provide a device of the class described adapted to be applied as a simple attachment or addition to common types of watch mechanisms wherein a main spring-driven member is disposed coaxially with and in parallel relation to a wheel for winding the spring.

A particular object is to provide mechanism of the class described wherein movement is transmitted to an oscillatable arm from both the spring-driven member and winding wheel therefor through the medium of teeth of spiral form and a toothed pinion which rotates about its own center and is movable substantially radially of the main spring axis while in mesh with the spiral teeth on the driven member and winding wheel.

Other objects will appear and be more fully pointed out in the following specification and claims.

Referring to the accompanying drawing which illustrates my device by way of example and not for the purpose of limitation, as applied to a spring-operated watch mechanism of common type:

Figure 1 is a front view of the watch having a preferred form of my indicator mounted thereon and with a portion of the face cover and dial broken away to show parts otherwise concealed;

Fig. 2 is a back view of the mechanism with the cover removed;

Fig. 3 is a part side view and part section taken on the line 3—3 of Fig. 1;

Fig. 4 is a fragmentary, somewhat diagrammatic, enlarged vertical section taken approximately on the line 4—4 of Fig. 2;

Fig. 5 is a detail plan view of the spiral tooth carried by the ratchet wheel, looking in the direction indicated by the line 5—5 of Fig. 4 and with the axial shaft shown in section;

Fig. 6 is a part plan view and part section taken approximately on the line 6—6 of Fig. 4, and

Fig. 7 is an enlarged plan view of a portion of

2

the arm carrying the pinion and with the supporting arbor therefor shown in section.

As shown in the drawing, the watch has a case indicated generally by the numeral 8, a removable back cover 9 and a transparent face cover or crystal 10. The movement is supported within the case on a back plate 11 and parallel front plate 12 and there is a dial 13 supported in front of the plate 12. These plates and the dial are rigidly connected together and to the case in suitable manner. A winding knob 14 projects from the case to be manipulated to turn a gear 15 through suitable connecting means, including a stem and bevel gearing. The teeth of the gear 15 mesh with teeth formed on the periphery of a ratchet wheel 16 and this wheel is fixed on a shaft 17 having bearings in the plates 11 and 12 and connected to the main spring of the watch (not shown) within the main spring barrel indicated by the numeral 18. The main spring is of the common spiral form and has its inner end connected to the shaft 17 and its outer end to the barrel 18 so that the latter is turned in one direction (clockwise, Fig. 6) when the spring is under sufficient tension. Peripheral teeth 19 on the barrel 18 are adapted to drive a suitable gear train to actuate, in the usual manner, the hands 20 indicating the time by reference to the graduated dial 13. It will be evident that the watch movement hereinbefore described is of common type illustrative of suitable environment for the preferred form of my improved indicator presently to be described.

I provide an arcuate scale 21 (Fig. 1) on the dial 13 where it may be readily observed through the crystal 10 and a small hand 22 to indicate the tension of the main spring by reference to the scale 21. The latter is graduated and provided with indicia indicating at one end that the spring is fully wound and at the other end that it is unwound or has insufficient tension to operate the watch. There are also intermediate indicia affording readings in fractions of full tension. The hand 22 is fixed on a pin 23 having a bearing in the front plate 12 and a small toothed pinion 24 is also fixed on the pin 23. This pinion is in continuous mesh with a toothed segment 25 which is integral with an arm 26 and the latter is fixed on an end of an arbor 27. Bearings for the arbor 27 are formed in the plates 11 and 12 so that the arm 26 is adapted to oscillate upon the plate 12 about the axis of the arbor 27. Details of the hand operating mechanism and scale 21 may be varied widely within the scope of the present invention.

A second arm 28 is connected to the arbor 27 and extends between the opposed faces of the ratchet wheel 16 and main spring barrel 18. Rotatable on the end of the arm 28 remote from the arbor 27 is a small toothed pinion 29, disposed with its axis of rotation parallel to and midway between the opposed faces of the ratchet wheel and drum. This pinion is movable bodily with the arm 28 in an arc having its center at the axis of the arbor 27, this arc being approximately radial to the shaft 17 (see Fig. 6).

Formed on the face of the barrel 18 to mesh with the pinion 29 is a spiral tooth 30 having its convolutions uniformly spaced radially to correspond with the pitch of the teeth of the pinion 29. Another spiral tooth 31 is formed on the opposed face of the ratchet wheel 16 to mesh with the pinion 29 in a similar manner. As indicated in Figs. 5 and 6, the spiral tooth 31 winds in the reverse direction as compared with the tooth 30. That is to say, from its inner end 31a the tooth 31 extends counter-clockwise and spirally outward, whereas, the tooth 30 extends clockwise from its inner end 30a outward. The outer ends of the teeth 30 and 31 are indicated respectively by the numerals 30b and 31b. As further indicated in Figs. 4 and 6, the convolutions of the tooth 30 continue outward somewhat beyond the outer convolution of the tooth 31 and the convolutions of the latter approach the shaft 17 more closely than those of the tooth 30. Otherwise these teeth are opposite one to the other. The pinion 29 in its movement about the axis of the arbor 27 oscillates substantially radially of the spiral teeth 30 and 31 and is in continuous mesh with both of them.

The connection between the arbor 27 and arm 28 is preferably of the type shown in detail in Fig. 7. Thus the arbor is of elliptical shape in cross section and engages the arm 28 in a substantially square opening 32 in said arm. A slit 33 bifurcates the end portion of said arm which is constructed from sufficiently resilient material so that the respective end portions spring apart and permit slight oscillating movement of the arm relative to the arbor when the arbor is stopped through its connection with the arm 26. To limit oscillating movement of the arm 28, as indicated in Fig. 1, it may be formed to extend between stop pins 34 and 35, projecting from the face of the supporting plate 12. An angularly bent end portion 38 may also be extended through an opening 36 in the plate 12 to afford a stop for the self-winding mechanism in case the watch is provided with automatic winding mechanism.

In operation, when the watch is wound by means of the knob 14, the ratchet wheel 16 is turned in a clockwise direction (Figs. 2 and 5). Assuming that the main spring is in fully unwound or low tension condition the hand 22 will point to the zero mark on the scale 21 and the corresponding position of the pinion 29 will be at the inner extremity of the tooth 31. Now as the watch is wound the barrel 18 remains substantially stationary and the clockwise rotation of the wheel 16 by means of the tooth 31 causes the pinion 29 to turn about its center and to be moved substantially radially outward relative to the shaft 17. During this movement the pinion 29 merely rolls in mesh with the convolutions of the tooth 30 and the arm 28 turns the arbor 27 and actuates the arm 26, tooth segment 25 and pinion 24 to move the hand 22 to the right (Fig. 1) over the scale 21. When the main spring has been substantially fully wound in this manner the

arm 26 is stopped by the pin 35 with the hand 22 indicating the fully wound condition.

Overriding by the watch movement with respect to this fully wound position of the arm 26 is permitted by so positioning the outer end 31b of the tooth 31 as to cause it to release the pinion 29 before the spring has been wound excessively tight. With the indicator hand 22 in the fully wound position the main spring slowly rotates the barrel 18 in a clockwise direction (Fig. 6) while the wheel 16 and its tooth 31 remain stationary. This causes the spiral tooth 30 to turn the pinion 29 and to oscillate the arm 28 radially inward toward the shaft 17 with the axis of the arbor 27 as the center. Consequently the arbor 27 reverses the movement of the arm 26 which, through the segment 25 and pinion 24, slowly moves the hand 22 to the left along the scale 21 from the fully wound position.

To permit overriding by the watch movement relative to the zero position of the hand 22, the inner end 30a of the tooth 30 is so positioned that it disengages the pinion 29 and stops inward movement of the arm 28 at a suitable point in the cycle of operation. Relief is also afforded by the springing apart of the bifurcated end portions of the arm 28 relative to the elliptical arbor 27 thus allowing the arm 28 to swing slightly relative to the arbor, as indicated in dotted lines in Fig. 7. This feature is used to spring bias the arm 28 in an outward direction when released by the end 30a of the tooth 30 and in an inward direction when released by the end 31b of the tooth 31. Thus the tendency of the arbor 27 to spring back to its diagonal position in the square opening 32 causes the pinion 29 to spring radially, to the extent of the radial pitch, outward when released by the inner end 30a of the tooth 30 and inward when released by the end 31b of the tooth 31. The effect of this is to insure proper engagement of the pinion 29 with the spiral teeth at all times.

It will be evident that my device occupies space which is available within the cases of ordinary watches and does not require rearrangement of the watch mechanism. The teeth 30 and 31 are preferably cut on the faces of the barrel 18 and wheel 16 respectively, although in some watches it may be feasible to provide these spiral teeth on separate discs or as separate spirals attached to the faces respectively of spring driven and winding members.

For watches provided with self-winding devices the end portion 33 of the arm 26, when in its fully wound position constitutes a stop for the oscillating weight, thereby guarding against excessive winding and undesirable operation of the automatic winding movement. This stop feature may be used with or without the indicator hand and scale but it will be evident that the indicator shows when hand winding is necessary even where automatic winding mechanism is provided.

Having described my invention, what I claim as new and desire to protect by Letters Patent is:

1. In a spring tension indicator for mechanism having a rotary spring-driven member, a spring for rotating said member and a rotary spring winding member disposed in spaced parallel and coaxial relation to said spring-driven member, the improvements which comprise, teeth of spiral form disposed on the respective opposed faces of said members, a pinion movable substantially radially of the axis of said members between their opposed faces and having

teeth disposed to mesh simultaneously with the spiral teeth on said members, the tooth on said winding member being formed to move said pinion substantially radially in one direction during the spring winding rotation of said member, the tooth on the spring-driven member being formed to move said pinion substantially radially in the reverse direction during the normal rotation of said spring actuated member and said spiral teeth being of relatively unequal radial extent at their outer and inner ends to permit the stopping of radial movement of the pinion while rotation of the spring-driven member relative to the winding member continues, means including a scale and hand for indicating by reference to said scale the state of tension of said spring and means connecting said pinion to said hand for actuating said hand relative to said scale.

2. The indicator mechanism according to claim 1 in which stop means are provided to limit the movement of said hand at the opposite ends respectively of said scale and said means connecting said pinion to said hand includes means associated with said stop means for resiliently retaining said pinion in engagement with the spiral teeth during the reversal of movement of the pinion.

3. The indicator mechanism according to claim 1 in which said means connecting said pinion to said hand comprises an arbor disposed in

parallel relation to the axes of said members, an arm carried by said arbor and extending between said members, said pinion being rotatably mounted on said arm to impart oscillating movement thereto and means operatively connecting said arbor to said hand.

4. The indicator mechanism according to claim 1 which includes means for spring biasing the pinion radially inward when positioned at the outer extremity of its movement and radially outward when at the inner extremity of its movement.

5. The indicator mechanism according to claim 1 which includes an arm pivoted to oscillate in a plane parallel to the opposed faces of said spring-driven and winding members and operatively connected to said pinion and means for limiting oscillating movement of said arm to an arc corresponding approximately to the radial movement of the pinion.
